Patented Sept. 9, 1975

236,761

MIST HAIR STYLER

Norman A. Steinkamp, Chicago Heights, Ill., assignor to Sunbeam Corporation, Chicago, Ill.

Filed Jan. 14, 1974, Ser. No. 433,432

Term of patent 14 years

Int. Cl. D28—03

U.S. Cl. D86—10 F

FIG. 1 is a perspective view of a mist hair styler showing my new design;

FIG. 2 is a front end elevational view thereof;

FIG. 3 is a rear end elevational view thereof;

FIG. 4 is a side elevational view of the side not visible in FIG. 1;

FIG. 5 is a top plan view thereof; and

FIG. 6 is a bottom plan view thereof.

I claim:

The ornamental design for a mist hair styler, as shown.
